United States Patent Office.

H. C. HARDY, OF MUNCIE, INDIANA.

Letters Patent No. 66,148, dated June 25, 1867.

IMPROVED TABLE.

The Schedule referred to in these Letters Patent and making part of the same.

TO ALL WHOM IT MAY CONCERN:

Be it known that I, H. C. HARDY, of Muncie, in the county of Delaware, and State of Indiana, have invented a new and useful improvement in Tables; and I do hereby declare that the following is a full, clear, and exact description thereof, which will enable others skilled in the art to make and use the same, reference being had to the accompanying drawing, forming part of this specification.

The drawing is a perspective view of a table with my device attached for operating on the leaves to raise and lower them easily.

This invention relates to a new and useful contrivance for aiding in raising and lowering the leaves of an ordinary dining-table, and consists in connecting weights to hang under the bed of the table with the sliding supports usually employed to hold the leaves when they are raised, which weights draw upon the supports at the time the leaves are raised and throw them out under the leaves to support them. Attached to the supporters are also levers, which may be readily turned to raise the weights and throw the supporters back when the leaves are again lowered, thus making the raising and lowering of the leaves of a table easy and convenient.

An ordinary table is shown in the drawing, of which A is the bed, and B B the side leaves. C C are supports fitted on the frame E, as usual, which turn on the pivots a a. D D are weights hung to chains or cords, b b, one end of which is fastened to the bed and the other to the supports C C near their ends at c. Between the points c c and the pivots a a are attached chains or ropes, d d, on the supporters C C, which chains are connected at the other ends with the ends of the levers e e pivoted on the under side of the leaves B B near their outer edge, nearly midway between their ends, as shown clearly in the drawing. The levers e e are provided with crank-handles, e', with which they are turned conveniently by the hand when the leaves are lowered without requiring the person to stoop to push in the supporters C C. When the leaves are raised the weights D D act automatically to draw out the supporters C C under the leaves of the table.

Having described my invention, I claim as new, and desire to secure by Letters Patent—

The weights D D and levers e e, in combination with the supporters C C, arranged and operating substantially as and for the purposes herein described.

H. C. HARDY.
